ALARM CONTROL FOR CLOCKS

John E. Coogan, Carbondale, Pa.

Application September 23, 1931, Serial No. 564,630

6 Claims. (Cl. 161—1)

This invention relates to improvements in alarm systems and more particularly to an improved means of preventing tampering with alarm clocks and other like devices.

5 In its preferred embodiments the invention comprehends generally the use of various types of alarm clocks for rousing sleepers at a predetermined hour, which alarm clocks are associated or connected with a bed in such a manner 10 that, while the bed is occupied, the alarm mechanism will be in operative or ringing condition, while when the bed is unoccupied the alarm mechanism will be disconnected. The improvements involve suitable electrical and/or mechanical 15 connections between the bed and the clock whereby the alarm mechanism proper is, as indicated above, rendered operative when the bed is occupied and rendered inoperative when the bed is unoccupied. In addition, the invention 20 comprehends the use of means for preventing access to the controls of the alarm clock, said means including locking mechanism associated with the alarm releasing mechanism so that the controls cannot be reached during the period 25 when the alarm should normally be operative, i. e., for about one hour after the time set for the alarm.

The foregoing objects are cited as illustrative of the scope of the improvements comprehended 30 in the present invention, but it is to be understood that it is not intended to be limited thereto, except as such limitations are clearly imposed by the appended claims.

In the drawings like numerals refer to similar 35 parts throughout the several views, of which

Fig. 1 is a schematic view of an alarm system showing the circuit connections and operative parts of an alarm clock and a bed post upon which is mounted a switch mechanism, the alarm bell 40 being included in the circuit;

Fig. 2 is a side perspective of the clock shown in Fig. 1 the rear portion being broken away to show the details of the locking mechanism;

Fig. 3 is a detail view of a modification of the 45 circuit shown in Fig. 1, showing means for directly operating the striker of an alarm clock;

Fig. 4 is a perspective view of the striker control support shown in Fig. 3;

Fig. 5 is a vertical section of the back of a 50 clock showing means for directly attaching same to a bed post, together with a modified cover locking arrangement; and

Fig. 6 is a view similar to Fig. 1 showing the 55 use of a mechanical control system for the alarm and cover locking mechanism.

Fig. 7 is a front view of the arrangement shown in Fig. 6.

Referring now to Fig. 1, there is indicated diagrammatically an alarm clock 10 of conventional construction having a dial 11, bezel 12, back 60 plate 13, casing 14, and a cover 15, hingedly mounted on an extension 16 of the casing 14 by any suitable means, such as hinge 17, situated at the top of the clock. The casing 14 may be extended downwardly as indicated at 7 to provide space for bell transformers and the like, indicated generally at 18, the transformer compartment including a top plate 19 which also serves as the bottom of the clockwork chamber, and a bottom plate 20, as well as a rear wall or plate 65 21. The plate 21 is apertured as indicated at 22, to receive the tongue 23 of the cover 15 which tongue is apertured to receive the bolt 24. The latter member also serves as the core of a solenoid 25, the core being provided with a spring 70 26 adapted to normally urge or force the bolt out of the aperture in member 23, and thus permit the cover to be raised and lowered. Suitable leads 27, 28, are provided for the coil and they will be described more in detail hereinafter. An 75 electric bell 29 is mounted in the casing as shown and is in turn provided with leads 30, 31.

The alarm system of the clock mechanism may comprise a spring motor 40 provided with a winding key 41, the motor shaft 42 being provided 80 with a gear 43 in mesh with a gear 44 on shaft 45, the two said shafts being mounted in the frame supports 46, 47, of the clock. On the shaft 45 is mounted a gear 48 adapted to mesh with a striker mechanism 49 mounted on shaft 85 50. There is also mounted on the shaft 50 an arm 51 provided with a dog or tooth 52 at the free end thereof, the said member 52 being adapted to be engaged by a detent 53 carried on the end of the spring arm 54, which is secured at one end 90 by a suitable securing means, including a screw 55. Intermediate its length the spring arm 54 is adapted to contact with a bushing 55' secured to the gear wheel 56 forming a part of the alarm control gear train. The gear 56 is in mesh with the main driving mechanism of the clock, not shown, and is adapted to be driven in the usual manner. On the opposite side of the bushing 55' there is provided a bushing 57 having a notched 95 section 58. The notched section 58 is so configured as to have a perpendicular side and a slanting side for a purpose to be described more in detail hereinafter.

The alarm control mechanism comprises a disk 110

60 having an integral tooth or projection 61, the said disk being mounted for rotation on the control shaft 62 having a control handle or knob 63. Said shaft is supported or carried by the plates 46, 47, previously described. The tooth 61 may be set at any angular position desired by means of the control member 63, the angular position thereof determining the hour when the alarm is to function. When the gear 56 has 10 rotated to the point where the straight side of the notch 58 passes it, the gear and its associated parts will be forced outwardly by the spring member 54. This outward movement of the spring will carry the detent 53 beyond the upper portion of the catch 52, releasing the latter and permitting the striker mechanism 49 to be operated by the gear train motivated by the spring motor 40. The striker mechanism will continue to function while the member 61 rests in the notch 58, which 15 is usually more than long enough to permit the motor to expend itself. Upon the continuance of its travel the sloping section of the notch 58 tends to ride up on the cog or tooth 61 thus forcing the gear 56 and associated mechanism inwardly towards the clockwork frame, thus forcing the spring member 54 backward until the detent 53 again engages the stop member 52. This position is usually reached at the top of the sloping section of the notch 58 and when the member 61 rides on the top or forward portion of the collar 57 the alarm mechanism is in the 20 arrested or off position.

A novel feature of the present invention resides in an improved switch mechanism associated 35 with this alarm control mechanism. As above indicated the spring member 54 is secured to the mounting plate 46 by means of a screw 55. The latter is adapted to engage a spacer post 70 suitably disposed between the mounting plates 40 46, 47.

The switch mechanism comprising contacts 71, 72, is mounted on the screw 55, suitable insulating bushings or posts 73, 74, being provided to space the same from each other and from the 45 clockwork support. The member 73 will serve as a retaining member for the spring 54. A washer 75 insulates the screw 55 from the jack or switch members. The tongue 71 of the switch member is adapted to bear on the gear 56 and to be urged into contact with the switch member or 50 tongue 72 when the spring 54 urges the gear 56 outwardly at the time the notched portion 58 passes the tooth 61 of the alarm control. When the gear 56 has been forced back into the normal 55 running position the contact 71 follows it and breaks contact with the member 72.

These contact members are provided with leads 60 76, 77, passing respectively to a pair of secondary terminals on the transformer 18, the latter being provided with the usual line leads 76, 77. The transformer is provided with a further secondary winding having a lead 27 connected to the main lead 76, and a lead 28, the latter being directly connected to the coil 25 of the detent mechanism 65 controlling the bolt 24. Upon the closing of the switch members 71, 72, the coil 25 is energized forcing the bolt 24 into the latch member 23 against the action of the spring 26, which normally keeps the bolt out of contact with the latch. 70 It will thus be seen that when the alarm is actuated, the cover is closed and maintained closed for the period during which the member 61 remains in engagement with the notch 58 of the collar 57 on the alarm gear.

75 As intimated hereinbefore, the invention com-

prehends the use of a control mechanism associated with the bed and adapted to be actuated by the weight of a person resting in said bed. Referring more particularly to Fig. 1, there is shown at the right thereof a bedpost 80 having a 80 spring 81 therein, which spring is adapted to work against a piston 82. The latter member is provided at its bottom portion with the usual caster mechanism 83, including a roller 84. The member 80 is provided near its bottom with a flange 85 adapted to serve as a stop for the casing 86, of the switch mechanism, the latter being screw-threaded to engage the screw threaded bottom portion of the post 80. A nut 88 is provided to maintain the casing 86 in position. The 90 member 86 is preferably made of a suitable insulating material such as a molded phenolic condensation product or it may be made of wood, hard rubber or other suitable materials.

Mounted on the casing is a clip jaw 90 of a 95 switch, designated generally by the numeral 91, the member 90 being secured to the casing by suitable means such as a screw 92 which is adapted to act as a terminal member. A terminal member 93 is likewise provided on the casing 100 and is connected to the cooperating switch member 94 through a flexible lead 95. The switch member or tongue 94 is mounted on an insulating support 96 which in turn is positioned and secured on the piston 82 by means of spacing 105 bushings or washers 97, 98, the latter being preferably screwed on the threaded bottom portion of the piston. In order to maintain this switch mechanism dust-free, a flange 99 is secured to the bottom of the member 83 and is so configured 110 and arranged as to engage the inner walls of member 86 in sliding contact.

While the casing 86 has been described as being made of a suitable structural insulating material, the invention comprehends the use of any 115 desired metal, such as steel, iron, brass, etc., the terminals being suitably insulated therefrom in any known manner.

It will now be appreciated that upon the imposition of any weight on the bed member 80, comprising preferably one leg of said bed, will be carried downwardly against the action of the spring 81 and in this downward movement will carry the casing 86 and the switch member 90, the latter being forced into engagement with the 125 cooperating switch member 94, thus closing the circuit in the legs 100, 101, of the circuit through the transformer, the clock switch and the alarm bell.

It will also be seen that when the alarm goes 130 off, while a person is yet in bed, the detent coil 25 will be energized and the cover locked in position; the circuit through the bed post switch 91 and bell will be completed through the clock switch and the transformer, thus causing the 135 bell to be operated.

Upon the release of the weight from the bed, caused by a person rising, the jaws of switch 91 will be forced apart and the bell circuit broken. However, the detent circuit will still be in operation, due to the closure of the clock switch, which is maintained during the period the alarm control cog 61 rests in the notch 58 of the alarm gear. This period being roughly one hour, although, of course, it may be arranged for any 145 predetermined period by suitably configuring the notch so the detent will be energized for such a period, and it will be impossible for a person to open the cover and disconnect the alarm mechanism. Further, if during this period a person 150

returns to bed the switch 91 will be again closed and the bell 29 again set in operation. It will thus be appreciated that the system just described is adapted for use with ordinary alarm 5 clocks containing an alarm mechanism. While the latter has been disclosed as comprising a part of a spring wound motor driven clock, it will be appreciated that it is likewise applicable to an electrically driven clock without any change in 10 the structure of the latter, or of the switch mechanism just described.

Where it is desired to use a mechanically operated alarm bell, such as is normally furnished and made part of an alarm clock, the improvements 15 of the present invention may be incorporated with such mechanism without involving any disturbance or mutilation of the several parts. Referring more particularly to Figs. 3 and 20 4, the modification therein disclosed for controlling the alarm of striker mechanism comprises a supporting platform 110 of bakelite, wood, brass or any suitable structural material upon which is mounted a coil, 111, the latter being connected to the operating circuit by means of the usual leads 30, 31. This coil mechanism thus replaces the bell mechanism 29, and is adapted to be normally urged against the striker lever 49 by means of a suitable spring 113, the coil and spring being suitably mounted on the platform or support 25 110. When the alarm switch is operated the coil 111 is energized and the plunger 112 retracted, thus permitting the striker to oscillate and ring the alarm bell. Upon opening the circuit either at the alarm switch or at the switch 30 35 91 the coil is de-energized and the plunger forced into contact with the striker bar by means of the spring 113, thus rendering the striker inoperative.

This striker control mechanism may be readily 40 applied to the ordinary alarm clock and associated with the switch members 71, 72, and their associated parts in the following manner. The bushing 73 is attached in the manner above disclosed and there is superposed thereon a support 45 or platform 114 which is secured to the member 73 by suitable means such as screws or rivets 115. The support 114 may be provided with a strap 116, this strap being suitably fastened or secured to the clockwork plate 47. The coil support 50 110 is mounted on the cross piece 114, in any suitable manner as by means of screws or rivets, 117. It will thus be seen that by the provision of the cross piece 114 supported on the members 46, 47, and the bushing 73, the coil 111 and its support 110 may be suitably positioned with respect to the striker mechanism and at the same time maintained out of contact with the clockwork and further without involving any further 55 space requirements. In other words, the coil 111 60 may be associated with the clock mechanism without increasing the size of the space necessary for the latter.

Referring now to Fig. 5 there is shown an improved means for mounting a clock mechanism 65 directly on a bed. The locking cover of the clock 120 is permanently associated with the switch casing 86 in any suitable manner. The cover or casing is provided with inturned peripheral flanges 121 having apertures 122 adapted to receive 70 locking arms 123 and hold the latter in position in apertures 124, formed in the shoulder rim 125 of the casing member 14. The locking rods 123 are pivoted respectively at the ends 126, 127, of the rocker arm 128 which is mounted in the 75 yoke 129 formed on the wall 13 of the clock. The

rocker arm is provided with a depending arm 130 connected to the plunger arm 24 of the solenoid 25. It will thus be seen that when the coil is deenergized the spring 26 will draw the arm 24 inwardly causing the rocker arm 128 to rotate about its pivot and withdraw the locking rods 123 from the aligned apertures 122, 124, in the casing and the cover. When the coil is energized the plunger is forced downwardly and the rocker arm is rotated or oscillated in the reverse direction forcing the locking arms 123 in the aligned apertures in the casing and cover and locking the two parts together. The general operation of this clock is the same as those above described, as by this means one cannot remove the clock from its support and cover 120 until after the expiration of the predetermined period of time, so that it is impossible to tamper with the alarm control mechanism.

Referring now to Fig. 6 there is shown a mechanical adaptation of the improvements of the present invention, in which a suitable alarm clock is removably mounted directly on a bed post 80, the back plate 134 of the clock being rigidly attached thereto by means of a support bracket 100 133. The bracket is clamped between a collar 131, which is either formed as an integral part of the post casting or threaded thereon and collar 132 adapted to be screwed on the lower portion of the post against the support 133. In the post 80 105 is embedded a spring, not shown, which is adapted to work against the piston 135, so that when the bed is occupied the post 80 and the clock case affixed thereto will move downward.

An arm 136 extends from a peripheral flange 110 83 formed at the bottom of the piston 135, and passes through an aperture 144 in the plate 134. The arm 136 is connected to a vertically positioned rod 137 which is supported by guide members 138, 138' and attached at its upper end to a 115 member 140. A triangular support 139 pivotally supports the member 140, the outermost end of which rests between the bi-furcated ends of a dog 141. The dog is pivotally attached to a support 143 which in turn is affixed to the frame support 120 47 thus providing for its upward movement and consequent disengagement from the cog wheel 48 when the bed post and attached clock case is pressed downwardly.

It will be noted that when the dog 141 is in 125 this position the alarm will ring at the predetermined time and will continue to ring as long as the bed is occupied, that is to say, as long as the post 80 is pressed to its downward position. However, when the bed becomes unoccupied and the 130 post, because of the spring working against the piston, moves upwardly, carrying with it the clock case, the dog 141 will consequently be moved downwardly, engaging the gear wheel 48 and locking the striker mechanism.

The mechanical modification also comprehends the automatic case locking feature. When the alarm sounds, as hereinbefore described, the disk 56 moves outwardly and carries with it the rod member 145, which is supported by the guide 140 members 146, 146' attached to the frame supports 46 and 47. The rod 145 is formed at one end with a bifurcated member 151 adapted to engage the disk 56 while its other end is pivotally attached to an angle arm 147.

The angle arm is pivotally mounted on a triangular support 148 firmly attached to the back plate 13 of the clock case. To the other end of the angle arm 147 is pivotally attached a plunger rod 149 which is adapted to be moved upwardly 150

through an aperture 150 in the clock case when the bifurcate 151 is carried forward by the disk 56, thereby locking the back plate 134 to the clock case.

- 5 It will be also noted that since the disk 56 remains forward for a period of time determined by the design of the cam 58 as shown in Fig. 1 in the bushing 57, the case will remain locked not only during the sounding of the alarm but 10 until the disk is moved backward by the notched portion of the bushing 57 riding away from the tooth 61, also shown in Fig. 1, which time, depending upon the size of the notch, may advantageously be at least one hour.
- 15 In order to lock the plate 134 securely to the bottom of the clock case, there is provided a tongue or projection 152 formed on the clock case extension. The tongue is adapted to engage with a recess or slot 153 formed in the plate 134.
- 20 Referring to Fig. 7, there is shown a clock mounted in the operative position upon a bed post. It will be seen that sufficient clearance is provided for the downward movement of the clock when the spacing 81, shown in Figure 1 is 25 compressed and the clock is in its lowermost position.

While I have shown and described the preferred embodiment of my invention, I wish it to be understood that I do not confine myself to the 30 precise details of construction herein set forth, by way of illustrations, as it is apparent that many changes and variations may be made therein, by those skilled in the art, without departing from the spirit of the invention, or exceeding 35 the scope of the appended claims.

What I claim is:

1. In a clock having an alarm control mechanism, and means for adjusting the same to operate at predetermined times, an enclosing member 40 for said adjusting means, a lock for said enclosing member, a signal, means actuated by said alarm control mechanism for operating said signal and said lock, and other means operatively connected with said signal for arresting the operation of the same without affecting the actuation of the alarm control mechanism.

2. In a clock having an alarm control mechanism, and means for adjusting the same to operate at predetermined times, an enclosing member 50 for said adjusting means, a lock for said enclosing member, a signal, means actuated by said alarm control mechanism for operating said signal and said lock, and weight actuated means

operatively connected with said signal for arresting the operation of the same without affecting the actuation of the alarm control mechanism.

3. In a clock having an alarm control mechanism which operates for a predetermined period of time, and means for adjusting the same to operate at any desired instant, an enclosing member for said adjusting means, a lock for said enclosing member, a signal, means actuated by said alarm control mechanism for operating said signal and said lock, said lock being in locking position during the operation of said alarm control mechanism, and other means operatively connected with said signal for arresting the operation of the same without affecting the actuation of the alarm control mechanism. 80

4. In a clock having an alarm control mechanism with means for adjusting the same to operate at predetermined times, an enclosing member for said adjusting means, a lock for said enclosing member, a signal, electrical means operated by said alarm control mechanism for actuating said signal and said lock, and other electrical means operatively connected with said signal for arresting the operation of the same without affecting the actuation of the alarm control mechanism. 85

5. In a clock having an alarm mechanism which operates for a predetermined period of time, and means for adjusting the alarm control mechanism to operate at any desired instant, an enclosing member for said adjusting means, a lock for said enclosing member, a signal, electrical means actuated by said alarm control mechanism for operating said signal and said lock, 105 said lock being maintained in locking position during the operation of said alarm control mechanism, and other electrical means operatively connected with said signal for arresting the operation of the same without affecting the actuation 110 of the alarm control mechanism. 115

6. In an alarm clock having an alarm control mechanism which operates for a predetermined time period, and means for adjusting the alarm control mechanism to operate at any desired instant, an enclosing member for said adjusting means, a lock for said enclosing member, and electrically operated means actuated by said alarm control mechanism for positioning and maintaining said lock in locking position during 120 the operation of the alarm control mechanism. 125

JOHN E. COOGAN.
